(57) **CLAIM**

The ornamental design for a vacuum cleaner roller, as shown and described.

DESCRIPTION

FIG. 1 is a perspective view of a vacuum cleaner roller, illustrating our new design;

FIG. 2 is a first side view thereof;

FIG. 3 is a second side view thereof;

FIG. 4 is a right side view thereof, shown in enlarged scale;

FIG. 5 is a left side view thereof, shown in enlarged scale;

FIG. 6 is a third side view thereof; and,

FIG. 7 is a fourth side view thereof.

In FIGS. 1-7, the two different shades of gray color represent a color contrast, but not any particular color.

1 Claim, 7 Drawing Sheets
